(57) **CLAIM**

An ornamental design for a door chime, as shown and described.

DESCRIPTION

FIG. 1 is a perspective view of a door chime;
FIG. 2 is a front elevation view of the door chime of FIG. 1;
FIGS. 3-6 are left, right, top and bottom views of the door chime of FIG. 1; and,
FIG. 7 is a back view of the door chime of FIG. 1.
The broken lines depict unclaimed environmental subject matter.

1 Claim, 7 Drawing Sheets
